His Attorney.

UNITED STATES PATENT OFFICE.

GEORGE E. STACK, OF BALLSTON, NEW YORK, ASSIGNOR TO GENERAL ELECTRIC COMPANY, A CORPORATION OF NEW YORK.

MOTOR-CONTROL SYSTEM.

1,326,004.

Specification of Letters Patent. Patented Dec. 23, 1919.

Application filed July 31, 1918. Serial No. 247,478.

To all whom it may concern:

Be it known that I, GEORGE E. STACK, a citizen of the United States, residing at Ballston, in the county of Saratoga, State of New York, have invented certain new and useful Improvements in Motor-Control Systems, of which the following is a specification.

My invention relates to the control of electric motors and has for its object the provision of means whereby an electric motor may be started, stopped and generally controlled in a reliable, simple and efficient manner. My invention relates more specifically to the control of variable speed motors for use in applications where it is desirable upon restarting after stopping to have the motor automatically come to the speed which it had before stopping. In one embodiment of my invention I employ what is known as a "push button control" by which is meant control in which any of the operations is accomplished automatically upon the operation of a push button. Ordinarily there is provided a starting push button which brings the motor to its normal running speed; a stopping button for stopping the motor; a "fast" button which speeds up the motor above normal and a "slow" button for decreasing the speed of the motor. All of these buttons may not in all cases be necessary. In carrying out my invention in one form I provide means whereby if the motor should be running at a certain speed and the motor is stopped, for instance by pressing a stop button, upon again starting the motor, as for instance by pressing the "start" button, the motor will automatically be brought up to the speed which it had before stopping.

In the specific arrangement which I have disclosed I employ a pilot motor for operating the control mechanism for both the starting and the speed variation and provide means whereby, upon restarting, the pilot motor will operate the control mechanism when the "start" button is pressed until the speed is reached which the motor had before stopping. The specific means whereby this is accomplished consists of a control member operated by a pilot motor for effecting the starting and speed variation and an auxiliary member, which, when it is engaged by the control member, stops the movement of the control member so that

there can be no further progress through the start button. In this position, however, the members are locked together so that if either the "slow" or "fast" button should be pressed the pilot motor will again operate to either slow down or speed up the motor. When the "stop" button is pressed the members will be unlocked leaving the auxiliary member where it happens to be and moving the control member back to the initial position. Upon again pressing the "start" button the control member will therefore move until it engages the auxiliary member which, of course, will correspond to the speed at which the motor was running before stopping.

Other objects and purposes of my invention will appear in the course of the following specification in which I have shown my invention embodied in concrete form for purposes of illustration.

In the accompanying drawing Figure 1 is a diagrammatic view of the system as a whole and Figs. 2 and 3 are details of the locking mechanism.

Referring to the drawing, A represents the armature, F the series field, and F' a shunt field of the electric motor to be controlled. I have shown this motor as being reversible through the reversing switch 10. R, R¹ and R² represent sections of starting resistance which are cut out of circuit by electromagnetic switches or contactors 11, 12 and 13. 14 is a line contactor for closing the motor circuit initially. 15 and 16 are field protective contactors for opening the motor circuit in case the field circuit is broken or otherwise interrupted. 17 is a relay contactor for closing the circuit of the shunt contactors when a push button is pressed and makes a maintaining circuit for itself so that the push button need only be closed for an instant.

The control mechanism proper consists of a controlling member 18, pivoted at 19, and operated by a pilot motor 20 through worm gearing 21, so as to consecutively engage the contacts 22, 23 and 24 which energize the contactors 11, 12 and 13 respectively, to cut out the section of resistance. This arm also engages a segment 25 which is connected by a conductor 26 with field protective contactor 16 and field F'. F. R. represents the field resistance which causes the variation in speed of the motor after the motor has come up to its normal running speed. This re-

sistance is provided with contacts 27 engaged by the control arm 18 so that as the arm passes off of the starting section a continuous movement will bring it into engagement with the field contacts and insert field resistance. Pilot motor 20 is reversible, being provided with two field windings f and f' which are closed by the contactors 28 and 29 respectively. In other words, when the contactor 28 closes, the pilot motor will operate in one direction, and when the contactor 29 is closed, the pilot motor will operate in the reverse direction.

In order to provide that when the motor is stopped with the control arm on any of the field resistance contacts 27, upon restarting the arm will be brought back to that point, I provide the auxiliary arm 30 which is pivoted concentrically with the main control member 18. This arm is provided with two contacts 31 and 32 engaging contact segments 33 and 34 respectively and is arranged to remain in any position in which it is left. It is likewise provided with means for locking itself to the control arm 18 when the two arms come together when the arm 18 is beneath the arm 30. The arrangement whereby this is accomplished is shown in Figs. 2 and 3, from which it will be seen that locking arm 35 is pivoted to the arm 30 and has on its free end a hooked portion 36 provided with a roller 37. The arm 35 is provided with a lifting core 35' for electromagnet 35'' which lifts the core 35 against the tension of spring 38. The arrangement is such that as the arm 18 comes under the arm 30 the roller 37 rolls on the arm 18 until it drops over the edge, as shown in Fig. 3 and locks the arm 18 against independent movement. The projection 39 prevents the arm 18 from ever going beyond the arm 30. The arm 30 is likewise provided with a switch arm 40 having a projection 41 which is engaged by a roller 44 on the arm 18 to move the switch arm out of engagement with the contact 42 and into engagement with the contact 43. The result is that when the arm 18 passes under the arm 30 the switch 40 is operated to break contact at 42 to stop the pilot motor and makes contact at 43 which is in the circuit of the magnet 35''. The magnet 35'' is not at this time energized however, therefore the two arms remain locked together. When, however, the "stop" button is pressed the magnet 35'' is energized and the arms are unlocked so that the arm 18 may return to its initial position leaving the arm 30 where it stands. The roller 44 at the end of the arm 18 in the initial position of the arm engages an angular switch arm 45. This switch insures that the arm is brought back to starting position before the motor circuit can be closed after the stopping of the motor. There are also provided switches

46, 47 and 48 which are operated by a roller 49 on arm 30 at the positions shown for purposes hereinafter described.

As thus constructed and arranged the operation of my system is as follows: With the parts in the position shown in Fig. 1 and the switch S closed, by closing the switches S' and 10 the contactors 15, 16 and the field winding F' will be energized from the positive side of the line, through the switch S', winding of contactor 15, field F', contactor 16 to the segment 25, thence to the arm 18 and conductor 50 to the opposite side of the line. This energizes the shunt field winding and closes contactors 15 and 16. If now one of the "start" buttons is pressed, the contactor 17 will be energized from the positive side of the line to conductor 51, through the stop buttons, conductor 52, through the contact of overload relay 53, through the contacts of contactors 16 and 15, through the winding of contactor 17, through the start buttons to the switch 45, conductor 52', interlock 56 on line contactor 14 and conductor 57 to the opposite side of the line. The contactor 17 will now close and make a maintaining circuit for itself at interlocking contact 58, which circuit will be independent of the "start" button. The closing of contactor 17 completes the circuit for the line contactor 14 through the contacts of contactor 17 back to line through conductor 57. The closing of contactor 14 closes the circuit through the main motor armature and resistance R, R' and R''. The closing of contactor 14 also completes a circuit for the winding of contactor 28 to close the circuit of the pilot motor, the circuit being as follows: from the positive side of the line through conductor 51, winding of contactor 28, through the interlock 59 on contactor 14, thence through the segment 33, contact 31, through the switch 40, thence to conductor 50 and back to the other side of the line. The closing of contactor 28 completes the circuit for the pilot motor through the field f resistance r , the circuit being from the positive side of the line, conductor 51, through the contacts of contactor 28, field f and armature of the pilot motor, resistance r and conductor 50 to the negative side of the line. The pilot motor will now start and move the arm 18 over the contacts 22, 23 and 24 successively to energize the contactors 11, 12 and 13 and short circuit resistance sections R, R' and R'' until the motor finally comes up to normal running speed. Assuming that the arm 30 has been left in the position shown, the arm 18 will continue to move after it leaves contact 24 and segment 25. When the arm 18 comes under the arm 30 the switch 40 is operated to deenergize the contactor 28 and stop the pilot motor. The switch 40 is also moved to make contact at 43 so as to close

this part of the circuit of the magnet 35". The magnet not being energized at this time, however, the latch 35 (Fig. 3) will drop down over the arm 18 and the two arms will 5 be locked together and the pilot motor will be stopped. The motor will therefore be brought up to the speed at which it had been left before stopping.

Assuming now that the motor is running 10 at this speed and it is desired to speed up further, one of the "fast" buttons is pressed whereupon the contactor 28 will be again energized to start the pilot motor for forward movement. In this movement the arm 15 18 will engage the projection 39 on arm 30 and move the latter forward with it. This movement may be continued so long as the "fast" button is pressed until the switch 48 is reached, which will stop the pilot motor.

20 If the stop button should now be pressed with the motor running at its highest speed the arm 18 will be released from the arm 30 and returned to its initial position. Upon again restarting, the arm 18 will be brought 25 up to this highest speed.

Assuming that the motor is running at the highest speed, or for that matter at any speed above normal, if one of the "slow" buttons is pressed, the contactor 29 will be 30 energized through the conductor 60, switch 46 and switch 45, which has been closed on contact 61 in the forward movement of the arm 18, and conductor 52'. This will cause the pilot motor to be energized through the 35 field winding f' so as to reverse the pilot motor. Since the two arms are now locked together they will both move backward and slow down the motor. So long as the "slow" button is pressed this slowing operation may 40 be carried on until the switch 47 is opened by the roller 49 on the arm 30, which opens contactor 29. Switch 46 is emergency switch in series with switch 47.

It will thus be seen that I have provided 45 a motor control system of the push button type in which a motor may be brought to any speed by the operation of push buttons, and upon being stopped by a push button and restarted, will return to the speed which 50 it had before stopping.

While I have described my invention as embodied in concrete form and as operating in a specific manner in accordance with the provisions of the patent statutes, it should 55 be understood that I do not limit my invention thereto, since various modifications thereof will suggest themselves to those skilled in the art without departing from the spirit of my invention, the scope of 60 which is set forth in the annexed claims.

What I claim as new and desire to secure by Letters Patent of the United States, is:

1. The combination with an electric motor of means for starting the same, means 65 for varying the speed after the starting

means has operated including a manually operated normally inoperative switch for gradually increasing the speed of the motor and a similar switch for gradually decreasing its speed, and means whereby upon restarting the motor after stopping it will automatically return to the speed which it had before stopping. 70

2. The combination with an electric motor of means for starting the same, means 75 for varying the speed of the motor including a manually operated normally inoperative switch for gradually increasing the speed of the motor and a similar switch for gradually decreasing the speed and means 80 whereby upon restarting the motor after stopping it will automatically return to the speed which it had before stopping.

3. The combination with an electric motor of means for starting the same, a resistance 85 member for varying the speed of the motor, a pilot motor for operating the same to various positions to increase and decrease the speed of the motor and means whereby upon restarting the motor after stopping it will 90 automatically return to the speed which it had before stopping.

4. The combination with an electric motor of starting and speed regulating mechanism, a pilot motor for operating the same 95 to various positions, to start the motor and increase and decrease its speed and means whereby upon restarting the motor after stopping it will automatically return to the speed which it had before stopping. 100

5. The combination with an electric motor, of a starting mechanism therefor, a pilot motor for operating the same, speed regulating mechanism operated by the pilot motor to various positions to increase and decrease the speed of the motor after the starting mechanism is operated and means whereby upon restarting the motor after stopping it will automatically return to the speed which it had before stopping. 105

6. The combination with an electric motor of a pivoted starting member therefor, a pilot motor for operating the same, an independently movable member operated by the pilot motor to various positions to limit the movement of the starting member and means whereby upon restarting the motor after stopping it will automatically return to the speed which it had before stopping. 115

7. The combination with an electric motor of a pivoted starting and speed varying member therefor, a pilot motor for operating the same, an independently movable member operated by the pilot motor for limiting the movement of the starting member after the starting member has completed its starting movement and means whereby upon restarting the motor after stopping it will automatically return to the speed which it had before stopping. 120
125
130

8. The combination with an electric motor of a starting and speed varying member therefor, a pilot motor for operating the same, an independently movable member for limiting the movement of the starting member after the starting member has completed its starting movement and means whereby upon restarting the motor after stopping it will automatically return to the speed which it had before stopping.
9. The combination with an electric motor of a controlling member therefor, a pilot motor for operating the same, an auxiliary member arranged to be engaged by the controlling member to stop the pilot motor and lock the two members together, and independently controlled means for again starting the pilot motor to move both members so as to establish a new limit of operation for the pilot motor.
10. The combination with an electric motor of a controlling member therefor, of a pilot motor for operating the same, an auxiliary member arranged to be engaged by the controlling member to stop the pilot motor and lock the two members together, and means for unlocking the members and causing the controlling member to move backward from the locking position.
11. The combination with an electric motor of a controlling member therefor, a pilot motor for operating the same, an independently movable member arranged to be engaged by the controlling member and deenergize the pilot motor and independently operated means for restarting the pilot motor.
12. The combination with an electric motor of a controlling member therefor, an independently movable member arranged to be engaged by the controlling member and moved forward thereby after engagement, means for locking the members together so that they will move backward together and independently controlled means for unlocking the members so that the controlling member may be moved backward independently.
13. The combination with an electric motor of a controlling member therefor, a pilot motor for operating the same, independent switches for starting and stopping the pilot motor, an independently movable member arranged to be engaged by the controlling member to stop the pilot motor and a switch for energizing the pilot motor in a reverse direction to cause the controlling member to return.
14. The combination with an electric motor of a controlling member therefor, a pilot motor for operating the same, an auxiliary member arranged to be engaged by the controlling member so that the members will move forward together after engagement and having means for deenergizing the pilot motor, a switch for energizing the pilot motor so that the controlling member will be moved backward independently and a switch for energizing the pilot motor so that the two members will move forward together.
15. The combination with an electric motor of a controlling member therefor, a pilot motor for operating the same, an auxiliary member arranged to be engaged by the controlling member so that the members will move forward together after engagement and having means for deenergizing the pilot motor, means for locking the members together so that they will move backward together, a switch for energizing the motor to cause such backward movement and a switch for unlocking the members and causing the controlling member to return independently.
16. The combination with an electric motor of a starting and speed varying member therefor, a pilot motor for operating the same, a switch for energizing the pilot motor to move the member to start the motor, an auxiliary member movable over the speed varying positions and arranged to be engaged by the controlling member to stop the pilot motor, means for causing the auxiliary member to always move forward with the controlling member after engagement, means for locking the members together upon engagement so that they will move backward together, a switch for energizing the motor to cause the forward movement of the two members and a switch for unlocking the members and causing the control member to return independently.

In witness whereof, I have hereunto set my hand this 27th day of July, 1918.

GEORGE E. STACK.
